UNITED STATES PATENT OFFICE.

CITY OF CHICAGO, ILLINOIS, ASSIGNEE TO HAUER & BLACK, OF CHICAGO,
ILLINOIS, A CORPORATION OF ILLINOIS.

MACHINE FOR MAKING SURGICAL BANDAGES.

2,136,262.

Specification of Letters Patent. Patented Sept. 1, 1939.

Application filed September 26, 1938. Serial No. 2,136,262.

Recd. at the U.S. Patent Office, Sept. 1, 1939.

Edgar Hauer, of Chicago, Illinois, a citizen of the United States, residing at Chicago, in the county of Cook and State of Illinois, has invented what are believed improvements in Machines for Making Surgical Bandages, of which the following is a specification:

The primary object of this invention is to provide a machine of simple construction, which can be easily and rapidly operated, for making surgical bandages in accordance with the method disclosed in my co-pending applications, Serial No. 1,029,791, filed September 26, 1938.

As is well known to surgeons and others skilled in the dressing of wounds, it is essential that the bandage be so made that the longitudinal threads will not pull or pull out from the body of the bandage at the edges thereof because such free threads will be drawn into and embedded in the wound when the bandage is applied, thus irritating the wound and retarding its healing. It has been customary, therefore, in the manufacture of surgical bandages to secure the longitudinal threads at the edges of the bandage by tying them with fine, thin, wire-like threads, projecting from the edges of the bandage. This results in the longitudinal threads being cut off before or after the bandage is wound, so as to withdraw the several longitudinal threads of a stiff material, or other suitable material. It is very difficult, however, to secure all of the thread lengths in this manner and in the greater number of the cases this produces there are many of these thread lengths adhering to the edges of the bandages where they will be brought in contact with the wound when the bandage is wound and frequently left in the wound when the bandage is removed.

My present invention aims to provide a machine which will separate longitudinal threads of a fabric from which a series of bandages are to be made and then the fabric is to be wound, leaving a portion at each edge of the bandage in which the warp threads are compacted or compressed more closely together, leaving a warpless space between the bandages across which the warp or lifting threads extend.

Another object of the invention is the provision of a means for weakening or severing the warp threads extending across the warpless spaces whereby to divide the fabric into bandage strips.

Other objects and advantages of the invention will be apparent as the same is better understood in reference to the following description when considered in connection with the accompanying drawings.

Referring to the drawings—Figure 1 is a top plan view of the machine embodying my invention; Fig. 2 is a fragmentary view of the machine, certain portions being removed to show the parts disposed thereunder; Fig. 3 is a longitudinal sectional view of the machine shown in Fig. 1; Fig. 4 is an enlarged detail view of one of the separating mechanisms; Fig. 5 is an end elevation of the mechanism shown in Fig. 4, certain parts being broken away; and Fig. 6 is an enlarged sectional view showing one of the separators.

On the drawings 7 designates a frame of any suitable construction in which are supported a plurality of tension rollers or bars 8, a pair of 10, 11, 12 and 13, and a presser roller 14, all of well known or preferred construction.

The woven fabric 15, in the form of a bolt or roll, is positioned in the frame on a suitable spindle 16 from which the material is fed through the machine to a spindle 18 upon which it is wound, the roll during the winding operation being held in engagement with the feed rollers 10 and 11 by the presser roller 14 mounted in brackets 16 which are vertically adjustable on suitable guides 17. Power may be applied to the machine through a pulley 19 mounted on the shaft 18 from which the various rollers are driven through a suitably arranged train of gears or other driving mechanism.

Although the mechanism for winding the material from the spindle 18 onto the spindle 15 may be of any preferred construction, I have shown for purposes of illustration, in Figs. 1 and 2, the winding mechanism which forms the subject matter of my prior Patent No. 2,083,358, granted May 14, 1937.

A pair of shafts 21 and 23 is positioned transversely of the machine frame between the tension members 8 and the winding spindle 18, the shaft 21 having rotatably mounted thereon a plurality of wheels 24.

spaced apart on the shaft a distance equal to the width of the bandages to be made. Each of the wheels 24 is provided with a series of radially disposed slots 25 in which 5 are mounted the warp separators 26, one of which is shown on an enlarged scale in Fig. 6, from which it will be observed that the outer end of the separator is tapered as indicated at 27 to facilitate its projection between the warp threads of the fabric. These 10 separators are also provided with a lateral projection 28 adapted to engage in a cam slot 29 formed in the cam 31 fixedly mounted on the stationary shaft 21 adjacent the wheel 24. It will be observed that the cam slot 29 is provided with a high portion at its 15 upper side which will project the separators in succession beyond the periphery of the rotating wheels 24 as they travel around the cam. The projection of the separators through the fabric 13 will displace the warp threads in both directions from the tapered ends 27 of the separators so as to compress or compact the warp threads on each side 20 of the separators, leaving a warpless space between the compacted portions. For the purpose of holding the fabric in co-operative relation with the separators to insure the projection of the separators through the 25 plane of the fabric, I have mounted upon the shaft 23 a plurality of wheels 32 directly over and in alinement with the wheels 24. Each wheel 32 is provided with a series of slots or recesses 33 adapted to receive the ends of the separators projected from its companion wheel 24. The fabric is accordingly held down by the wheels 32 against the peripheries of the wheels 24 so that the separators will be forced through 30 the fabric between the warp threads as the fabric is fed along.

Between the separating devices and the winding spindle 15 I have mounted a roller or platen 34 and above the platen and adapted to co-operate therewith I have mounted a plurality of disks 35, these disks being spaced to correspond to the spacing of the separating devices and being disposed in alinement with the points of the separators. 45 The disks may be held in co-operative relation with the roller platen by any suitable mechanism. In the present instance, however, I have shown each disk as carried by an arm 36 pivoted on a transverse rod 37, the rear end of each arm being adapted to overlie a leaf spring 38 secured to the frame of the machine. In order to regulate the pressure of the disk against the platen, I have equipped each arm with an 50 adjusting screw 39 adapted to contact with the spring 38 and by means of which the pressure of the disk may be increased or diminished, as desired.

The disks 35 may be provided with peripheral sharp cutting edges and the pres-

sure upon the disks may be so regulated that the weft threads extending across the warpless spaces formed by the separators may be entirely severed as they pass between the disks and the platen. In this 70 event the bandages will be separated one from the other and will be wound up on the winding spindle 15 as distinct and separate bandages. Preferably, however, the disks 35 are rather dull and the pressure is 75 so regulated that the weft threads will be simply crushed and weakened by the disks so that the roll of connected bandages wound up on the winding spindle may be readily 80 broken off along the weakened lines of weft threads to provide the individual bandage roll.

It will be manifest that by means of my improved machine above described I am 85 enabled to produce a number of complete bandages during one passage of the fabric through the machine and, that the completed bandages will each have a velvety edge formed by the projecting weft ends and that the tensile strength of the bandages will be increased at the edges by the 90 compacted weft threads so that the bandages will not become torn or distorted when tightly applied to a wound.

In the above description I have referred 95 to the longitudinal threads as warp threads and transverse threads as weft threads, but it will be obvious that the machine is equally adapted for spacing and compacting weft threads and weakening or severing the 100 warp threads if it should be found desirable to run the fabric through the machine in a transverse direction. The terms warp and weft threads are, therefore, merely relative and I do not wish to be understood as limiting the action of the separating devices to the warp threads, nor the weakening and separating devices to the weft threads.

It is believed that my invention and its mode of operation will be sufficiently understood from the foregoing without further description and it will be obvious to those skilled in the art that various modifications in the structural details disclosed may be made without departing from the scope of 115 the invention.

I claim:

1. In a machine for making surgical bandages, the combination of mechanism for feeding a strip of fabric longitudinally 120 through the machine, means for separating longitudinal threads of the fabric, and means for weakening the transverse threads between said separated longitudinal threads.

2. In a machine for making surgical bandages, the combination of mechanism for feeding a woven fabric through the machine, means for displacing warp threads of the fabric to compact said warp threads adjacent a warpless space, and means for 125

weakening the filling threads extending across said warpless space.

3. In a machine for making surgical bandages, the combination of mechanism for feeding a woven fabric through the machine, and means for displacing warp threads from their original position in the fabric, said means comprising a plurality of separators and mechanism for projecting said separators through the plane of the fabric.

4. In a machine for making surgical bandages, the combination of a warp separating device, comprising a plurality of separators and means for projecting said separators through and withdrawing them from the fabric, and means for holding the fabric in co-operative relation with the separating device.

5. In a machine for making surgical bandages, the combination of a plurality of devices for separating warp threads of a woven fabric, said devices each comprising a radially slotted wheel, a tapered separator slidably disposed in each slot and mechanism for projecting the separators in succession beyond the perimeter of the wheel and through the fabric, and means for retaining the fabric in co-operative relation with said devices, said means comprising a wheel for each separator wheel provided with radial slots adapted to receive the ends of the separators projected through the fabric.

6. In a machine for making surgical bandages, the combination of a separator wheel, a series of radially disposed separators slidably mounted in said wheel, a cam for projecting said separators in succession beyond the perimeter of the wheel, and a companion wheel provided with a series of radially disposed recesses adapted to receive the ends of the projected separators.

7. In a machine for making surgical

bandages, the combination of a rotatable wheel, a series of radially movable separators carried thereby, and means for projecting said separators in succession beyond the perimeter of the wheel.

8. A machine for making surgical bandages including a flat separator adapted to be engaged by an operating cam and provided with a tapered separating end adapted to be projected through a woven fabric.

9. A machine for making surgical bandages including a tapered separator, means for projecting said separator through a woven fabric, and means for holding said fabric in co-operative relation with the separator.

10. In a machine for making surgical bandages, the combination of a plurality of separating devices spaced apart, each comprising a series of tapered separators and means for projecting the separators through a woven fabric whereby to produce a plurality of warpless spaces in the fabric, and a plurality of similarly spaced devices for severing the weft threads extending across said warpless spaces.

11. In a machine for making surgical bandages, the combination of means for separating warp threads of a woven fabric to produce warpless spaces adjacent which the warp threads are compressed or compacted, and means for severing the weft threads along said warpless space and between said compacted warp threads.

12. In a machine for making surgical bandages, the combination of mechanism for feeding a strip of fabric through the machine, and means for separating longitudinal threads of the fabric.
